UNITED STATES PATENT OFFICE.

JAMES THOMAS LITTLE, OF MISSOULA, MONTANA.

DOOR-STOP.

1,333,499.

Specification of Letters Patent.

Patented Mar. 9, 1920.

Application filed July 9, 1919. Serial No. 309,558.

To all whom it may concern:

Be it known that I, JAMES T. LITTLE, a citizen of the United States, and residing at Missoula, in the county of Missoula and State of Montana, (whose post-office address is 321 East Front street, Missoula, Montana,) have invented new and useful Improvements in Door-Stops, of which the following is a specification.

10 My invention relates to improvements in door stops.

An important object of the invention is to provide a device of the above mentioned character, adapted to be secured to a door, 15 and having an element to engage with the floor, for holding the door open at desired positions, such device being of simple construction and easy to operate.

Other objects and advantages of the invention will be apparent during the course 20 of the following description.

In the accompanying drawings, forming a part of this specification, and in which like numerals are employed to designate like 25 parts throughout the same,

Figure 1 is a side elevation of the device, with one side of the casing removed,

Fig. 2 is an edge elevation of the same,

Fig. 3 is a perspective view of the operating lever,

Fig. 4 is a perspective view of a stop rod,

Fig. 5 is a perspective view of the device applied to a door, a portion of the door being in section,

35 Fig. 6 is a longitudinal sectional view taken on line 6—6 of Fig. 2,

Fig. 7 is a transverse section taken on line 7—7 of Fig. 6,

Fig. 8 is an inner side elevation of a button or releasing element,

Fig. 9 is a detail section through a metal plate adapted to be secured to the floor, for receiving the stop rod, and,

Fig. 10 is a detail section taken on line 45 10—10 of Fig. 1.

In the drawings, wherein for the purpose of illustration is shown a preferred embodiment of my invention, the numeral 10 designates a preferably flat casing, one side of which may be provided with a removable cover, as is customary in the construction of locks.

The casing 10 is provided with a guide bracket 11, rigidly secured thereto and arranged therein, and this guide bracket has an opening which is preferably circular

for receiving a reciprocatory stop rod or element 12. This rod extends through a key-hole opening 13 formed in the lower end 14 of the casing 10. The rod 12 is provided at 60 its lower end with a shoe 15, preferably formed of rubber, and adapted to contact with the floor. The rod 12 is provided with a transverse pin 16 arranged within the casing 10, and preventing the rod 12 from moving downwardly beyond a certain distance, until the rod is turned upon its longitudinal axis, at a right angle to its normal position, at which time the pin 16 will pass through the keyhole opening and the rod 12 may be 70 removed from the casing 10. As shown in Fig. 1, the rod 12 carries a washer 17, engaging above the pin 16, and this washer engages a compressible coiled spring 18, surrounding the rod 12 and engaging the 75 bracket 11.

One edge of the casing 10 is closed by a face plate 19, detachably secured to the casing by screws 20. This face plate is provided with a longitudinal recess 21, leading 80 into a longitudinal slot 22. Mounted to reciprocate within the recess 22 is an operating lug or element 23, having a reduced shank 24, operating within the slot 22. This reduced shank is rigidly secured to a slide 85 25, arranged upon the inner side of the face plate 19. To the upper end of this slide is secured a housing 26 provided in its back with a longitudinal slot 27, and an opening 28 in its front.

The numeral 29 designates an operating bell-crank lever, pivoted within the casing 10, as shown at 30. The free end of this bell-crank lever extends into a slot 31, formed in the rod 12, and is thereby connected with 95 the rod and also prevents its rotation. This free end is provided with a lower curved or tapered face 32, which permits the inner arm of the operating lever to be swung downwardly whereby the free end thereof is 100 withdrawn from the slot 31, as indicated in Fig. 1. The rod 12 may then be removed, if desired.

The opposite end of the bell-crank lever 29 has a universal connection with a link 105 33, the opposite end of which is equipped with a latch-head 34, having a tooth 35, adapted to enter a notch 36, formed in the face plate 19, this face plate being shown as formed in a plurality of sections, but obviously it may be formed in one piece. The head 34 operates within the housing 26,

and when the lug 23 is depressed sufficiently, the tooth 35 moves within the notch 36, thereby locking the rod 12 in the upper position out of contact with the floor. To release the latch-head 34, a releasing element 37 is arranged within the recess or notch 36, which is T-shaped, and this element is moved inwardly by a button 39, projecting to the exterior of the face plate.

10 To apply the device to a door 40, a recess 41 is formed therein through its outer edge, and the casing 10 may then be inserted within this recess, the rod 12 being disconnected therefrom. This casing is held in place by screws or the like passing through openings 42 formed in the face plate 19. A vertical opening 43 is also provided for the rod 12. The face plate 19, however, is now removed by unscrewing the screws 20, the 15 latch-head 34 passing through the lower open end of the housing 26. The rod 12 is now passed through the opening 43 and into the casing 10 and through the spring 18, the rod being subsequently turned at a right angle 20 so that the pin 16 will prevent its displacement. The inner arm of the bell-crank lever 29 having been swung downwardly, its free end will enter the slot 31 by swinging it upwardly. The face plate 9 is now brought 25 in proximity to the head 34 and this latch-head passed therein, subsequently to which the face plate is secured to the casing 10. An outer face plate 44 fits within a recess 45, and is held in place by screws 46. This 30 face plate has openings 47 and 28 for the reception of the button 39 and the lug 23.

When the button 39 is pushed inwardly, the latch-head 34 is released, and the spring 18 projects the rod 12 downwardly, so that 40 the shoe 15 engages the floor. By moving the lug 23 downwardly, the bell-crank lever will elevate the rod 12 and when the tooth 35 enters the notch 36 the rod will be again locked in the upper position.

45 If desired, the shoe 15 may be omitted, and a metal plate 49 secured to the floor, in a suitable position. This plate may be provided with recesses or notches 50, for the reception of the lower end of the rod. This 50 construction is used when the device is applied to a heavy door.

It is to be understood that the form of my invention herewith shown and described is to be taken as a preferred example of the 55 same, and that various changes in the shape, size, and arrangement of parts may be resorted to without departing from the spirit of my invention, or the scope of the subjoined claims.

Having thus described my invention, I 60 claim:

1. A door stop of the character described, comprising a casing, a floor engaging element extending into the casing, a spring to move the element outwardly, a face plate connected with the casing and provided with a notch, a slide carried by the face plate, a housing secured to the slide, a latch-head arranged within the housing and adapted to engage within the notch, an element to move the latch-head from within the notch and extending through the exterior of the casing, connecting means between the latch-head and the floor engaging element, and means to move the slide in 75 one direction.

2. A door stop of the character described, comprising a casing, a floor engaging element extending into the casing, a spring to move the element outwardly, a face plate 80 having a notch, a housing slidably mounted upon the face plate, a latch-head arranged within the housing and adapted to engage within the notch, an element to move the latch-head from within the notch, connecting means between the latch-head and the floor engaging element, and means to move the housing in one direction.

3. A door stop of the character described, comprising a casing, a floor engaging element projecting into the casing, a spring to move the element outwardly, an operating lever pivoted within the casing and adapted to engage with the floor engaging element and disengage the same when swung in one 90 direction, a face plate detachably secured to the casing, a slide carried by the face plate, a housing secured to the slide, a latch-head arranged within the housing and adapted to engage within a notch in the face plate, 100 means to move the latch-head from engagement within the notch, means connecting the latch-head and the pivoted lever, and means to move the slide.

4. A door stop of the character described, 105 comprising a casing, a reciprocating floor engaging element extending into the casing, a spring to move the element outwardly, a bell-crank lever engaging the element, a slide arranged within the casing, a latch-head, a housing carried by the slide and receiving the latch-head, means whereby the latch-head may be locked in a set position and released, a link connecting the latch-head and the bell-crank lever, and means to 115 move the slide.

JAMES THOMAS LITTLE.
